UNITED STATES PATENT OFFICE

WALDEMAR L. LINDGREN, OF WAUKEGAN, ILLINOIS, ASSIGNOR OF ONE-HALF TO
JOHN E. ERICSSON, OF CHICAGO, ILLINOIS

DISHWASHING MACHINE

Application filed May 2, 1929. Serial No. 359,917.

My invention is concerned with dish washing apparatus of the type in which the dishes are carried past spray mechanism upon the upper run of an endless carrier consisting of 5 a pair of chains mounted upon suitable sprocket wheels and connected by parallel transverse rods, and it is designed to produce a device of the class described in which the articles being washed are supported not 10 only by the moving rods, but also by a series of small, parallel, stationary, longitudinally-extending wires or rods extending in the line of movement of the rods connected by the chains, so that as the chains are moved 15 the articles to be washed are shoved along on the longitudinal rods by their engagement with the transverse rods.

It also consists of a novel conveyor structure for use in dish-washing apparatus, but 20 which is capable of use elsewhere.

To illustrate my invention, I annex hereto two sheets of drawings, in which the same reference characters are used to designate identical parts in all the figures, of which,— 25 Fig. 1 is a central, vertical, longitudinal section through a dish-washing machine containing my invention;

Fig. 2 is a top plan view as seen in section on the line 2—2 of Fig. 1;

Fig. 3 is an enlarged detail in section on the line 3—3 of Fig. 2;

Fig. 4 is a similar view in section on the line 4—4 of Fig. 2; and

Fig. 5 is a similar view in section on the line 5—5 of Fig. 3.

In carrying out my invention in a preferred form, I employ a pair of side frame members 10 having the feet 11 adapted to rest on the bottom of a sink 12, in which the apparatus is ordinarily removably mounted. 40 The side pieces 10 are connected at their ends by transverse frame members 13 and 14, each of which has a lower transverse bar 15, through which screws 16 are passed to 45 connect the frames 13 and 14 with the abutments 17 on the ends of the side frame members. These transverse bars 15 have at their ends the upwardly-extending, triangular brackets 18, which constitute the support for 50 the skeleton tops 19 of said end frame pieces.

Journalized on or secured to the transverse shafts 20 and 21 are the pairs of sprocket wheels 22 and 23, and these sprocket wheels support and move an endless carrier or conveyor for the dishes, etc., which is preferably constructed as follows: 55

A plurality of parallel rods 24, extending transversely of the apparatus, are connected at their ends to a series of chain links 25, these links being best shown in Fig. 3, and each consisting of a flat piece of metal having the elongated slot 26 therein, with the sides thereof parallel except at the center 27, where they are curved on the arc of a circle and form an aperture large enough to receive the ends of the rods 24. Near these ends, the rods 24 have recesses 28 formed therein of a width sufficient to accommodate the end of one of the two links 25 which engage the ends of each rod, and of a depth 60 so that the distance between the bottoms of the recesses is slightly less than the distance between the parallel sides of the slots 26, so that the ends of the rods can be thrust through the apertures 27 and then slid to the 65 ends of the slots in the links. The rods 24 have therein immediately adjacent the flat-bottomed recesses 28 the annular channels 28^a of a width slightly greater than the thickness of a chain link and of a depth equal to the maximum depth of the recesses 28, so that the end of the link 25 in said channel 28^a is free to turn, as is necessary in passing over the sprocket wheels 22 and 23, while the rods 24 are held from turning in the ends 70 of the links 25 which engage the recesses 28, it being necessary, for reasons to be herein-after explained, to keep the rods 24 from turning as the endless conveyor formed thereby passes over its upper run. The channel 28^a is outermost at one end of the rod 24, while the recesses 28 are outermost at the other end of the same rod. By turning the adjacent rods end for end, the links 25 of a single 75 pattern can be accommodated to a single pattern of rod. 90

Suitable means, such as an electric motor geared down to a slow speed, will be connected to one of the shafts 20 or 21 so as to rotate the wheels in a clockwise direction 100

and thus feed the upper run of the endless carrier from left to right. For the purpose of washing the dishes as they are thus slowly advanced by the carrier, I provide, near the receiving end, a pair of transversely-extending, perforated, spray-pipes 29 and 30, which are connected by the piping indicated in dotted lines in Fig. 1 with the hot-water faucet 31, so that sprays of hot water 10 may be thrown upwardly through the conveyor from the pipe 29 and downwardly on the dishes carried thereby from the pipe 30. These pipes are preferably provided with the soap boxes 32, by which sufficient soap may 15 be taken up by the water passing through the boxes to form a suds, aiding in the cleaning of the dishes. Toward the discharge end of the carrier, I employ the similar spray tubes 33 and 34, similarly connected to the 20 faucet, but not provided with soap boxes, as of course, the rinsing water should be clear.

The apparatus thus far described, except as to the details of the chain links 25 and the rods 24, is substantially that shown in my 25 prior application No. 317,176, filed November 5, 1928. In said prior apparatus, in addition to the transverse rods to support the dishes, I employed a series of flexible wires coiled once about each rod as it passed the 30 same, and held in place by suitable annular grooves in said rods. I found, experimentally, that while this type of carrier enabled me to support small articles, such as knives, forks, spoons, etc., there was a certain tendency for the ends of said articles to pass between the transverse rods, and possibly interfere with their free discharge from the conveyor at the end thereof. To remedy this difficulty, I employ the novel construction 35 now to be described:

The end pieces 19 preferably are of a skeleton construction, as shown in Fig. 2, and have the straight inner sides 35 and the outer sides 36, which are likewise straight except for 40 the central portion thereof, which curves in, as seen at 37, in order to form a recess which is convenient in placing the dishes on the receiving end of the apparatus and removing them from the discharge end. The sides 45 36 have formed therein at suitable intervals the holes 38, and I form on the top of the frame what is in effect a plurality of longitudinally-extending small rods by employing a wire or wires 39, which, beginning at one 50 end, as at 40, are passed through an aperture 38 and there secured, and then extended parallel to the edge of the main frame to the opposite end and passed through the correspondingly located aperture 38, and then 55 turned toward the adjacent aperture, through which it is threaded and then brought up over the top of the bar or side piece 36, and then extended parallel to the first portion of the wire to the other end piece 36, where 60 65 the threading operation is repeated, and so

on, as clearly indicated in Fig. 2, until the entire surface of the frame just above the carrier is covered. The end of the wire will then be passed through the last aperture 38 at that end of the side piece 36, where it will be also secured in place.

If the transverse rods 24 were straight and of uniform diameter throughout, the wires or rods 39 would rest on the top of the rods 24, and there would be no means for propelling the dishes from the receiving to the discharge end of the apparatus. I might in effect embed the wires 39 in the rods 24 by making annular grooves in the rods in the vertical plane of each of the wires, but that would necessitate the employment of larger and heavier rods than is desirable, so that, in order to obviate this necessity, I preferably form the rods 24 as shown in Fig. 4, where it will be seen that they are formed with bends 42 therein, which bends produce recesses 43 on one side of a sufficient depth so that the wires 39 may be in effect embedded therein, so that articles placed on the wires will be carried along by the movement of the rods 24. The novel rod and chain-link construction described prevents the rods 24 from turning as they pass beneath the wires.

At the discharge end of the machine, I preferably employ a receptacle 44 for the knives, forks, spoons, etc., and this preferably consists of a trough-shaped piece of sheet metal secured at one side to the rear of the adjacent cross piece 15. The intention is that knives, forks, etc., may be allowed to progress to the discharge end and be shoved over the same and into the receptacle 44 by the ones back of them. If for any reason it is desired to stop them, and not allow them to fall into the receptacle, I turn the stop plates 45 from the position shown in full lines in Fig. 1 to the dotted-line position, in which the fingers 46 will extend up between the adjacent portions of the wires and engage the articles. These stop pieces 45 may consist of what is in effect an axial portion 47, with the fingers 46 projecting therefrom and the handle 48 formed on the outer end thereof. These axial portions 47 may be journaled at their inner ends in recesses formed in the abutments 49 and at their outer ends in recesses 50 formed in the ends of the frame 14.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In dish-washing apparatus, the combination with a frame, of wheels journaled towards the ends thereof, a pair of endless

- chains, closely spaced transverse rods connecting the chains and together therewith forming an endless carrier upon which articles will rest and be held thereon by gravity alone, and a plurality of small parallel rods extending longitudinally of the frame in the plane of movement of portions of said transverse rods, so that articles placed on the longitudinally-extending rods will be carried thereover by the transverse rods. 5
2. In a dish-washing apparatus, the combination with a frame, of pairs of sprocket wheels journaled toward the ends thereof, a pair of endless chains, a plurality of transverse rods connecting said chains, the ends thereof forming the axles of the chain links and co-operating with the sprocket wheels to drive the endless carrier formed by the chains and rods, and a plurality of small parallel longitudinally-extending rods connected to the ends of the frame, and co-operating with the upper side of the upper run of the carrier so that articles placed on the longitudinal rods will be shoved along said rods 10 by the endless carrier. 15
3. In dish-washing apparatus, the combination with a frame, of wheels journaled toward the ends thereof, a pair of endless chains, transverse rods connecting the chains and together therewith forming an endless carrier, and a plurality of small parallel rods extending longitudinally of the frame in the plane of movement of portions of said transverse rods, so that articles placed on the longitudinally-extending rods will be carried thereover by the transverse rods, said longitudinal rods being formed of wires laced into transverse frame members having apertures 20 therein for that purpose. 25
4. In dish-washing apparatus, the combination with a frame, of wheels journaled toward the ends thereof, a pair of endless chains, transverse rods connecting the chains and together therewith forming an endless carrier, a plurality of small parallel rods extending longitudinally of the frame in the plane of movement of portions of said transverse rods, so that articles placed on the longitudinally-extending rods will be carried 30 thereover by the transverse rods, and a receptacle secured to the discharge end of the frame so that articles carried upon the carrier will drop therein. 45
5. In dish-washing apparatus, the combination with a frame, of wheels journaled toward the ends thereof, a pair of endless chains, transverse rods connecting the chains and together therewith forming an endless carrier, a plurality of small parallel rods extending longitudinally of the frame in the plane of movement of portions of said transverse rods, so that articles placed on the longitudinally-extending rods will be carried 50 thereover by the transverse rods, a receptacle secured to the discharge end of the frame so that articles carried upon the carrier will drop therein. 55
6. In dish-washing apparatus, the combination with a frame, of wheels journaled toward the ends thereof, a pair of endless chains, transverse rods connecting the chains and together therewith forming an endless carrier, a plurality of small parallel rods extending longitudinally of the frame in the plane of movement of portions of said transverse rods, so that articles placed on the longitudinally-extending rods will be carried 60 thereover by the transverse rods, a receptacle secured to the discharge end of the frame so that articles carried upon the carrier will drop therein, and a stop member pivoted in the discharge end of the frame. 65
7. In dish-washing apparatus, the combination with a frame, of wheels journaled toward the ends thereof, a pair of endless chains, transverse rods connecting the chains and together therewith forming an endless carrier, and a plurality of small parallel rods extending longitudinally of the frame in the plane of movement of portions of said transverse rods, so that articles placed on the longitudinally-extending rods will be carried thereover by the transverse rods, a receptacle secured to the discharge end of the frame so that articles carried upon the carrier will drop therein, and a stop member pivoted in the discharge end of the frame normally in an inoperative position, but capable of being turned up into position so that it will stop articles and prevent their falling into the receptacle. 70
8. In dish-washing apparatus, the combination with a frame, of wheels journaled toward the ends thereof, a pair of endless chains, transverse rods connecting the chains and together therewith forming an endless carrier, a plurality of small parallel rods extending longitudinally of the frame in the plane of movement of portions of said transverse rods, so that articles placed on the longitudinally-extending rods will be carried thereover by the transverse rods, the frame having at the ends thereof transverse pieces having apertures therein through which a wire is threaded so that portions thereof form the longitudinally-extending rods. 75
9. In dish-washing apparatus, the combination with a frame, of wheels journaled toward the ends thereof, a pair of endless chains, transverse rods connecting the chains and together therewith forming an endless carrier, a plurality of small parallel rods extending longitudinally of the frame in the plane of movement of portions of said transverse rods, so that articles placed on the longitudinally-extending rods will be carried thereover by the transverse rods, the frame having at the ends thereof transverse pieces having apertures therein through which a wire is threaded so that portions thereof form the longitudinally-extending rods, and a stop member pivoted in the transverse frame piece at the discharge end having fingers adapted to be turned up between the longitudinal rods. 80
10. In dish-washing apparatus, the combination with a frame, of wheels journaled toward the ends thereof, a pair of endless chains, transverse rods connecting the chains and together therewith forming an endless carrier, a plurality of small parallel rods extending longitudinally of the frame in the plane of movement of portions of said transverse rods, so that articles placed on the longitudinally-extending rods will be carried thereover by the transverse rods, a receptacle secured to the discharge end of the frame so that articles carried upon the carrier will drop therein. 85

itudinally-extending rods will be carried thereover by the transverse rods, the frame having at the ends thereof transverse pieces having apertures therein through which a wire is threaded so that portions thereof 5 form the longitudinally-extending rods, a receptacle secured to the discharge end of the frame so that articles carried upon the carrier will drop therein, and a stop member pivoted in the transverse frame piece at 10 the discharge end and having fingers adapted to be turned up between the longitudinal rods.

10. In a dish-washing apparatus, the combination with a frame, of wheels journaled 15 toward the ends thereof, a pair of endless chains, transverse rods connecting the chains and together therewith forming an endless carrier, and a plurality of small parallel rods extending longitudinally of the frame in the 20 plane of movement of portions of said transverse rods, so that articles placed on the longitudinally-extending rods will be carried thereover by the transverse rods, said 25 transverse rods having recesses in one side thereof to receive the longitudinal rods and being pivoted in said chains so as to prevent any angular movement relative to the longitudinal rods.

11. In a dish-washing apparatus, the combination with a frame, of pairs of sprocket 30 wheels journaled toward the ends thereof, a pair of endless chains, a plurality of transverse rods connecting said chains, the ends thereof forming the axles of the chain links 35 and co-operating with the sprocket wheels to drive the endless carrier formed by the chains and rods, and a plurality of small parallel longitudinally extending rods connected to the ends of the frame, and co-operating 40 with the upper side of the upper run of the carrier so that articles placed on the longitudinal rods will be shoved along said rods by the endless carrier, said chains being composed of links with elongated slots therein, 45 said slots having parallel sides except at the center where the slots are widened to permit the insertion of the ends of the transverse rods when the parts are assembled, said rods 50 having grooves in the ends thereof with flat bottoms to co-operate with the parallel sides of the slots.

12. In a device of the class described, the combination with a frame, of pairs of sprocket 55 wheels journaled toward the ends thereof, a pair of endless chains, a plurality of transverse rods connecting said chains, the ends thereof forming the axles of the chain links and co-operating with the sprocket wheels 60 to drive the endless carrier formed by the chains and rods, and a plurality of small parallel longitudinally-extending rods connected to the ends of the frames and co-operating 65 with the upper side of the upper run of the carrier so that articles placed on the

longitudinal rods will be shoved along said rods by the endless carrier, said chains being composed of links with elongated slots therein, said slots having parallel sides except at the center where the slots are widened 70 to permit the insertion of the ends of the transverse rods when the parts are assembled, said rods having grooves in the ends thereof with flat bottoms to co-operate with the parallel sides of the slots and annular channels adjacent the grooves to receive the other ends of the links co-operating with the grooves in adjacent rods to permit the chain to pass around the wheels while holding the rods from turning on the upper run while it 75 co-operates with the longitudinally-extending rods.

13. In a device of the class described, the combination with a frame, of pairs of sprocket 80 wheels journaled therein, a plurality of parallel longitudinally-extending rods between the tops of the sprocket wheels, and a conveyor co-operating with the rods consisting of a plurality of transverse rods with recesses in one side thereof to receive 85 the longitudinally-extending rods and having a pair of opposed flat-bottomed slots in each end and adjacent thereto an annular channel of a depth equal to the greatest depth 90 of the slots, and links of a thickness substantially equal to the width of the slots and channel and having elongated slots therein with parallel sides and of a width equal to the diameter of the rods at the bottom of the annular channel except for the center 95 where it is wide enough to receive the ends of the rods in assembling the same.

14. In a device of the class described, the combination with a frame, of pairs of sprocket 100 wheels journaled therein, a plurality of parallel longitudinally-extending rods between the tops of the sprocket wheels, and a conveyor co-operating with the rods consisting of a plurality of transverse rods with recesses in one side thereof to receive 105 the longitudinally-extending rods and having a pair of opposed flat-bottomed slots in each end and adjacent thereto an annular channel of a depth equal to the greatest depth of the slots, and links of a thickness substantially equal to the width of the slots and channel and having elongated slots therein 110 with parallel sides and of a width equal to the diameter of the rods at the bottom of the annular channel except for the center where it is wide enough to receive the ends of the rods in assembling the same, the ends of the slots at one end of the link being curved to fit the bottom of the channel and at the other end to fit the full thickness of 115 the rods.

15. In a dish-washing machine, the combination with a framework, of two pairs of sprocket wheels journaled therein, and a skeleton carrier mounted upon the wheels 120

and consisting of rods having annular grooves in the ends thereof connected by sheet-metal links having elongated openings therein extending nearly to the ends thereof of a width slightly greater than the diameters of the bottoms of the annular grooves and having enlargements in the center thereof of a diameter slightly greater than the ends of the rods.

16. In a dish-washing machine, the combination with a framework, of two pairs of sprocket wheels journaled therein, and a skeleton carrier mounted upon the wheels and consisting of rods having annular grooves in the ends thereof connected by sheet-metal links having elongated openings therein extending nearly to the ends thereof of a width slightly greater than the diameters of the bottoms of the annular grooves and having enlargements in the center thereof of a diameter slightly greater than the ends of the rods, said rods also having additional grooves therein between the end grooves and co-operating with wires extending substantially parallel to the links and co-operating with said additional grooves so as effectively to divide the otherwise elongated openings in the carrier into short rectangular openings.

30 In witness whereof, I have hereunto set my hand, this 12th day of April, 1929.

WALDEMAR L. LINDGREN.
